UNITED STATES PATENT OFFICE.

LOUIS K. SCOTFORD, OF CHICAGO, ILLINOIS.

SOUND-BOX CONSTRUCTION.

Application filed January 23, 1920. Serial No. 353,513.

To all whom it may concern:

Be it known that I, LOUIS K. SCOTFORD, a citizen of the United States, residing at Chicago, in the county of Cook and State of Illinois, have invented certain new and useful Improvements in Sound-Box Constructions, of which the following is a specification.

My invention relates to sound reproducing machines, and particularly to means for mounting the vibration transmitting bar and needle holder on a sound box on knife-edge or pointed supports without the use of springs for holding the various elements in contact with the knife edges or points.

In order to truly reproduce recorded sound, it is necessary that the movements of the needle be transmitted to the vibration transmitting bar with minimum lost motion. In view of the fact that the relative movement of the needle with respect to the sound box is slight, the communication between the needle holder, vibration transmitting arm and the diaphragm must be so sensitive as to reproduce faithfully and clearly the recorded sound. I have found that the best form of mounting the various elements going to transmit the recorded sound from the needle to the diaphragm includes mounting the vibration transmitting arm on points or knife edges, thereby reducing friction to a minimum. I am aware of the fact that the mounting of the various parts on knife edges is old, as this mounting has been practiced considerably in the past and is employed at the present time. However, the present arrangements employ springs for maintaining the contact of the various parts against the knife edges, and springs possess inherent faults which hinder perfect functioning of the parts to faithfully reproduce the recorded sound. My invention provides a knife edge or pointed support for the needle holder and vibration transmitting bar without using springs. Furthermore, it provides means for adjusting within certain limits the engagement between the knife edges and the parts mounted thereon.

One of the objects of my invention is to provide in a sound box knife edge supports for the vibration transmitting bar and needle arm without using springs or equivalent means.

Another object is to provide a knife edge mounting for vibration transmitting arms and means for adjusting the engagement between the knife edges and the supported parts.

A further object is to provide a knife edge support for sound box construction which will be simple, easily adjusted and economical to make.

A still further object is to improve sound box construction for successful commercial use.

By referring to the drawings, the objects of my invention will be apparent.

In the drawings,—

Figure 1 is a front elevational view of a sound box embodying my invention;

Figure 2 is a side elevation of the box of Figure 1;

Figure 3 is an enlarged fragmentary view partially in section showing the preferred knife edge construction of my invention;

Figure 4 is a horizontal sectional view on line 4—4 of Figure 3;

Figure 5 is a sectional view on line 5—5 of Figure 3;

Figure 6 is a view similar to Figure 3 showing a modified form of my invention;

Fig. 7 is an enlarged view of certain details of construction; and

Figure 8 is a section taken on line 8—8 of Figure 6.

My invention is shown in connection with a sound box 10 having the usual diaphragm 11 at the center of which is secured the upper end of the vibration transmitting bar 12. Extending from the rear side of the sound box 10 is an elbow-shaped tone-arm connector 13, which is adapted for association with a tone arm, and arranged so that the free end is parallel to the diaphragm.

My invention also contemplates a needle holder separate from the vibration transmitting arm. On the rear side of the sound box, that is, on the same side with the tone arm connector 13, is suitably mounted a bracket 14 having a horizontally disposed opening 15 therethrough. The lower portion of the vibration transmitting arm 12 is bent backwardly and terminates in an enlargement or head 16 in which is formed a horizontally disposed wedge-shaped opening 17 and having a vertically extending aperture 18 therethrough. The needle holder

of my invention has its upper end 19 shaped similarly to the enlarged end 16 of the vibration transmitting bar, and is provided with a wedge-shaped opening and a vertically disposed aperture therethrough similarly arranged to the corresponding parts in the enlarged portion 16 of the vibration transmitting bar. For bodily longitudinal movement in the opening 15 of the bracket 14 I mount two knife edged members 20, 21, which are alike in every respect. These members have the portions indicated by the reference characters 20, 21 of cylindrical shape, terminating in rounded rear ends 22. The other portions of the members are flattened, forming wedges or knife edge members 23. In Figure 4 it will be noted that the members 23 are cut out at 24 for a purpose to be hereinafter explained. These members are mounted as shown in the figures of the drawing so that the knife edge portions 23 extend beyond each end of the bracket 14 and engage the V-shaped openings in the head 16 of the vibration transmitting bar 12 and the needle holder 19. Through the vertically disposed apertures in the heads 16 and 19 are passed pins 25, which pins have reduced heads 26, and between the heads and the body portions of the pins are formed recesses 27. For cooperating with the pins and engaging the recesses 27 I provide top and bottom links or straps 28 which have head portions 29 providing a cut-out part in size just sufficient to pass over the reduced head 26 of the pins 25 and having a knife edge 30 for engaging the recesses 27 of the pins 25. In assembling the device the knife edge members 20 and 21 are inserted in back to back relation, as shown in Figures 3 and 4 of the drawing, and then the heads 16 of the vibration transmitting bar 12 and of the needle holder 19 are positioned thereon, the pin previously having been inserted in the apertures thru these heads, whereupon the engaging links 28 are applied as shown in Figure 3. For tightening the device to properly adjust the members 16 and 19 to move on the knife edges 23, I employ a set screw 31 carried in the side of the bracket 14. This screw is provided with a point engaging the rounded ends 22 of the members 20 and 21 so that inward or outward movement of the screw will move the members 20 and 21 to properly tension the links 28 and thereby adjust to a nicety the bearing of the members 16 and 19 on the knife edge members 23. The knife edge members 23, as before stated, have centrally cut-out portions 24. This is for the purpose of avoiding contact with the pins 25 and at the same time permitting the knife edges to function as such. Preferably the width of the openings 24 is but slightly greater than the diameter of the pins 25, which is for the purpose of preventing side-

wise movement of the needle holder and vibration transmitting bar.

I so position the parts that the axis of the needle, which is retained in the recesses 32 of the needle holder by a set screw 33, is in alignment with the axis through the portion 13^a of the tone arm connector. With this construction it is possible to employ my sound box in connection with both "zig-zag" and "hill-and-dale" records. The sound box may be mounted on the tone arm in the position shown in Figure 2 for playing "zig-zag" records. By reason of the fact that the needle is in axial alignment with the tone arm connector 13 the box may be turned through an angle of 90 degrees into the position of Figure 1, so that "hill-and-dale" records may be reproduced. This feature is of great advantage, as will be apparent to those skilled in the art. It may here be observed that with my invention it is possible to reproduce "hill-and-dale" and "zig-zag" records with a single sound box, the quality of the reproduction in each case being the same. This is brought about by the novel method of mounting the needle holder with respect to the tone arm connector. Furthermore, it may be observed that I have provided a knife edge mounting for a vibration transmitting bar and needle holder eliminating entirely the springs which have proved to be of uncertain quantity and which in order to admit the parts to function properly must always be uniform, which characteristic is hard to attain when quantity production of springs, sound boxes and parts is sought.

In the modification shown in Figure 6, the bracket has been extended to overlie the needle holder and adjacent end of the vibration transmitting bar, both of which have portions extending into an opening in the bracket. In Figure 6 the vibration transmitting bar 12 has a head portion 34 having formed on one side of a vertical axis therethrough two V-shaped recesses 35, one above the other, and on the opposite side a single V-shaped recess 36, the bases of the recesses lying in the same vertical plane. Similarly, the needle holder is provided with a head 37 having recesses arranged similarly to those of the head 34, but positioned in the opposite direction. At the vibration transmitting bar side of the bracket is securely fixed a knife edge 38 for engaging the recess 36 of the head 34. For separating the needle holder and vibration transmitting bar I provide a pair of pointed spreaders 39, the angle of the points of which is sharper than the angle of the recesses 35. As a means of securing adjustment of the knife edge construction of Figure 6, the knife edge 40 which supports the needle holder is mounted to have bodily movement of the bracket, and this movement

is governed by a set screw 41 suitably positioned to engage the rear of the knife edge 40. In this construction it will be noted that I have secured the same relation between the needle holder and vibration transmitting bar as I have in the first form, and that the uniformity of movement between the needle holder and vibration transmitting bar in both cases is the same. When the arrangement of Figure 6 is used in connection with the sound box the various parts are so proportioned that the axis of the needle carried in the needle holder will lie in the axis of the tone arm connector 13^a in the same manner as described in connection with the arrangement of the first form.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention.

I claim:

1. In a sound box construction, a needle holder and a vibration transmitting bar each mounted thereon and located in spaced lateral relation, and means connecting said needle holder and said vibration transmitting bar for transmitting movement from one to the other.

2. A sound box construction having a vibration transmitting bar and a needle holder, said members being maintained in spaced relation, means supporting said members on said sound box, said means including knife edge members, and inelastic means associated with said needle holder and said vibration transmitting bar for maintaining the same in engagement with said knife edge members.

3. A sound box construction having a vibration transmitting bar and a needle holder, said members being maintained in spaced relation, means supporting said members on said sound box, said means including knife edge members, inelastic means associated with said needle holder and said vibration transmitting bar for maintaining the same in engagement with said knife edge members, and means for adjusting the engagement of the parts on the knife edge members within certain limits.

4. In a device of the class described, including in combination a vibration transmitting bar and a needle holder in lateral spaced relation thereto, a bracket depending from the sound box, said bracket supporting knife edge members engaging said vibration transmitting bar and needle holder, means connecting said vibration transmitting bar and needle holder for maintaining the same in operative relation on said knife

edge members, and means for adjusting the operative relation of said needle holder and vibration transmitting bar.

5. A sound box having a vibration transmitting bar and a needle holder, means for transmitting movement from the needle holder to the vibration transmitting bar, said means including a pair of parallel members extending between the needle holder and vibration transmitting bar, and means engaging said holder and bar for maintaining same in association with said parallel members.

6. A sound box of the class described, having a needle holder and a vibration transmitting bar, a bracket depending from the lower portion of the sound box and having an opening therein, said vibration transmitting bar being supported at one end of said bracket and the needle holder at the other end thereof, and means transmitting movement from the needle holder to the vibration transmitting bar.

7. A sound box construction including separated vibration transmitting bar and needle holder, the same being mounted in spaced relation and included in a vertical plane normal to the plane of the diaphragm, knife edge members adapted to support said vibration transmitting bar and needle holder to permit rocking thereof, and means extending between said vibration transmitting bar and needle holder for maintaining the latter in engagement with said knife edge members.

8. A sound box construction including separated vibration transmitting bar and needle holder, the same being mounted in spaced relation and included in a vertical plane normal to the plane of diaphragm, knife edge members adapted to support said vibration transmitting bar and needle holder to permit rocking thereof, means extending between said vibration transmitting bar and needle holder for maintaining the latter in engagement with said knife edge members, and means for adjusting the engagement of the vibration transmitting bar and needle holder with respect to said knife edge members.

9. In a sound box construction, a needle holder and a vibration transmitting bar separately pivoted on said box in spaced lateral relation, and an articulated connection between said needle holder and vibration transmitting bar for constraining similar movement in the two members.

10. In a sound box construction, a needle holder and a vibration transmitting bar mounted on said box in such manner as to bring the outer end of the vibration transmitting bar and the inner end of the needle holder in substantially the same horizontal plane and in spaced lateral relation, and means connecting said needle holder and vi-

vibration transmitting bar for transmitting movement from one to the other.

11. In a sound box construction, a needle holder and a vibration transmitting bar mounted on said box in such manner as to bring the outer end of the vibration transmitting bar and the inner end of the needle holder in substantially the same horizontal

plane and in spaced lateral relation, and an articulated connection between said needle holder and vibration transmitting bar for transmitting movement from one to the other.

Signed at Chicago, Illinois, this 14th day of January, 1920.

LOUIS K. SCOTFORD.
